UNITED STATES PATENT OFFICE

HUBERT E. BAKER, OF MUSKEGON, MICHIGAN, ASSIGNOR TO THE BRADY CONVEYORS CORPORATION, OF CHICAGO, ILLINOIS

SKIP LOADING APPARATUS

Application filed May 28, 1929. Serial No. 366,630.

My invention relates to skip hoists and the means for filling the same, and my main object is to design the said means and the skip with a peculiar relation for automatic operation.

A further object of the invention is to provide the filling means with a gate which has no physical connection with the skip when loading the latter, so that slight variations in the positions of the gate or skip will not affect the filling operation.

A still further object of the invention is to render the skip subject to automatic hoisting without other controls than the weighting of the skip when fully loaded.

Another object of the invention is to dispose the skip free of any deterring influences, so that it will at all times draw its lifting cable tautly and occasion no slack in the same.

A significant object of the invention is to provide a simple electrical control for the release of the filling gate from closed to open position.

An additional object of the invention is to embody a simple switch device automatically controlled by the skip to induce the hoisting thereof.

A final but nevertheless important object of the invention is to build the apparatus of few and rugged parts which are durable and may operate for long periods without disorder or attention.

With the above objects in view and any others that may suggest themselves from the specification and claims to follow, a better understanding of the invention may be had by reference to the accompanying drawings, in which—

Figure 1 is an elevation of the apparatus, in which the skip is shown near its bottom position;

Fig. 2 is a similar view showing the skip at the bottom position and the gate in loading position; and

Fig. 3 is a detailed section on the line 3—3 of Figure 2.

In the art of skip hoists the effort to render them automatically operative has led to tim-

ing devices and other appliances of a complicated and undependable nature. Thus, connections have been made between the skip and the loading gate wherein these parts are interdependent, and therefore hoisting elements necessarily required timing for the proper cooperation with the loading apparatus. Needless to say, difficulties have resulted from variations in the timing, so that the mechanism lacked harmony and efficiency; also, the question whether the skip would be fully or partially loaded when hoisted was problematical. It has therefore been my intention to depart from the difficulties and uncertainties of installations of the past and to provide an apparatus which functions freely and accomplishes the objects outlined to their fullest extent.

In carrying out the invention, 5 denotes the bin or hopper from which material is to be loaded into the skip 6. The latter is of conventional design and is wheeled as indicated at 7 to ride upon the inclined track 8 of the hoist. The usual bail 9 and lifting cable 10 apply to the skip 6.

The track 8 is provided with an inclined frame member 11 which extends alongside the hopper chute 5a and carries a side rod 12 on which is pivoted the gate 13 for the chute 5a. Figure 1 shows the latter closed by the lower portion of the gate and when the gate is swung in a clockwise direction to assume a position shown in Figure 2, the lower end of the chute 5a opens and secures communication by way of the gate with the skip 6, as clearly shown in Figure 2.

Under normal conditions, when the gate 13 maintains the chute 5a in closed position, a latch 14 retains a side pin 15 of a plate 15a mounted on the gate against departure, locking the gate in closed position. The latch is held by a spring 16 which draws upon a connecting rod 17 linked to the latch. The latch is fulcrumed at 18 to the frame member 11 and extends as indicated at 19 to make a connection with the armature 20 of a solenoid 21 also carried by the frame member 11, the function of the solenoid when energized being to draw upon the latch with the

effect of opening the same relative to the pin 15 of the gate.

The frame member 11 carries a downward extension 22 which is fitted with a simple switch 23 which is closed by pressure upon a roller bearing lever 24. The skip has a cam 25 opposite the switch 23, and as the skip approaches bottom the cam 25 forces the lever 24 of the switch to close the latter with the effect that the switch 23 is in an electrical circuit with the solenoid and the closing of the switch energizes the solenoid with the effect of opening the latch 14. The weight of the gate 13 is so distributed that it will depart of itself from the closed position as soon as the pin 15 is released, and the gate will therefore swing in a clockwise direction and partly enter the skip 6 as shown in Figure 2.

With the gate open and in connection with the skip, the loading of the latter ensues, the weight of the skip from its load causing it to sink toward the track 8 by reason of a flexible connection between the skip and its wheels 7. As shown, the skip rests on cantilevers 26 drawn by springs 27 and fulcrumed in bearings 28 carried by skip plates 29. Thus, normally the skip is maintained in a high position relative to its wheels, but when weighted it sinks to a limited extent.

The sinking of the skip in the direction of its track is utilized for the control of a switch 30 which closes the circuit of the hoisting motor (not shown). As shown more clearly in Figure 3, the skip carries underneath it a roller 31 which is adapted to depress a plate 32 pivoted from a standard 33 whose base 34 is built on the track 8. The effect upon the plate 31 is to depress a roller bearing lever 35 which closes the switch 30, the plate 32 having a return spring 36 to automatically restore it to normal position free of the lever 35 when released by the skip roller 31. It will thus be evident that when the skip becomes fully loaded and secures the closing of the switch 30, the hoisting mechanism will become operative to lift the loaded skip.

The skip carries on the side a plate 37 in which is pivoted a projecting lever 38 which is weighted below the pivot as indicated at 39. The skip also has a lug plate 40 to limit the lateral swing of the weight 39 and prevent the lever 38 from moving in a downward direction.

The gate 13 has a roller bearing lug 41 in the path of the lever 38 as the skip ascends, the effect of the lever upon the lug 41 being to impinge upon the same and thus swing the gate with a return motion for purposes of closing the chute 5a. The lever 38 and the lug 41 are so disposed that the gate will be swung slightly beyond its normal return position before the lever 38 can clear the lug 41 on the further ascent of the skip. The extended travel of the gate is represented by the ad-

vance of the gate pin 15 deeply into the latch 14 after it has wiped over the nose 14a of the latch. In doing this, the pin has forced the latch out, the latter immediately returning to closed position once the pin is within it. The weight of the gate then slightly swings it forward to locate the pin near the outlet of the latch. 70

When the skip again descends, the lever 38 simply trips under the lug 41 of the gate as shown in Figure 1, and then assumes the position of rest indicated in Figure 2.

In assuming the open or skip loading position, the gate is relieved of shock by being provided with a bumper pin 42 which strikes an angle lever 43 backed by a cushion spring 44 carried by the chute 5a. Thus, the swing of the gate to open position does not terminate with a shock.

It will be seen that the novel apparatus provides a freely assembled combination. The opening of the gate is accomplished freely by gravity as soon as the latch is opened; yet the gate is not made to open until the skip has descended to a receptive position. Since the gate follows the skip in this respect, the slight deviation in the height of either the gate or skip will not produce any disorder or hardship; in other words, the gate connects with the skip by a free and following action. 85 Relative to the lifting time for the skip, I provide for the logical moment, which is that when the skip is full, and make no exception. The action is thus positive and does not depend on any timing devices which may prejudice the operation of the hoisting mechanism or the proper cooperation of the skip with the loading mechanism. The skip simply hangs from the hoisting cable until it is full, when it closes the hoisting circuit, assuring a full load each time it ascends. 100 The effect of the ascent of the skip upon the gate is purely mechanical, since the weighted skip spaces the cam 25 from the lever 24 of the switch 23, so that no effect will be had upon the switch and upon the latch controlled thereby. However, should the return trip of the cam 25 by any circumstance actuate the latch, no work or harm will be done, as the cam will have passed the switch by the time the gate has swung back to a position affected by the latch. 105

Electrically, the circuit of the solenoid could be designed for the operation of the switch only on the down course of the skip, so that the ascent of the skip will have no effect whatever upon the latch. Relative to the switch 30, the plate 32 is made sufficiently long to receive the effect of the roller 31 at points slightly higher or lower than the prescribed bottom limit of the skip travel, in order to allow for inaccuracies in the hoisting mechanism. 110

In conclusion, it may be said that the novel apparatus embodies a mechanism of few and simple parts which are of a rugged and dependable nature. The apparatus is devoid 115

of complicated or frail parts and its electrical appliances for the circuits are of simple and dependable design.

I claim:

- 5 1. A skip hoist comprising a wheeled skip, a track therefor, a flexible suspension between the skip and the wheels, a switch associated with the track and pressure-operated to energize the hoist, and a depressor carried by 70
10 the skip and adapted to transmit pressure to the switch when the skip sinks from a predetermined weight.
2. A skip hoist comprising a wheeled skip, a track therefor, a flexible suspension between 75
15 the skip and the wheels, a switch in the track and pressure-operated to energize the hoist, a yieldable lid over the switch and adapted to transmit pressure thereto, and a pendent roller carried by the skip and adapted to ride
20 with pressure upon the lid when the skip sinks from a predetermined weight.
3. A skip hoist comprising a wheeled skip, a track therefor, a flexible suspension between the skip and the wheels, a switch associated 80
25 with the track at the bottom travel limit of the skip and pressure-operated to energize the hoist, and a depressor carried by the skip and adapted to transmit pressure to the switch when the skip sinks from a predetermined
30 weight.
4. A skip hoist comprising a wheeled skip, a track therefor, a yieldable supporting connection between the skip and the wheels whereby the skip may yield toward the track 85
35 when loaded, hoist actuating means, the skip having an actuating portion adapted to engage said hoist actuating means in the loading position of the skip, and said yieldable supporting connection permitting engagement of said portions through the sagging of said skip toward said track under a predetermined weight of material.
5. In combination with a hopper having an outlet and a gate for the latter tiltable from 90
40 closed to open position and having an abutment carried by the gate, a skip hoist comprising a skip positioned for inclined travel opposite the gate, a lever carried by the skip and engageable with the abutment on the
45 ascent of the skip, a weighted extension of the lever maintaining the latter in position to assume said engagement, and a back stop to prevent the lever from yielding when in engaged position.
- 55 6. In combination with a supply chute having skip actuated closure unlatching means, a skip hoist having skip actuated means comprising a member adapted to be momentarily intercepted by a portion of said skip just 95
50 short of the loading position of the skip, skip actuated means for closing said closure and presenting the same to engagement by said unlatching means, a yieldable support for said skip permitting the same to sag out of
55 the path of said latch actuating means when
